UNITED STATES PATENT OFFICE.

HARRY PRICE, OF BOSTON, MASSACHUSETTS.

OIL VAPORIZER AND BURNER.

1,252,301.

Specification of Letters Patent. Patented Jan. 1, 1918.

Application filed March 19, 1917. Serial No. 155,690.

To all whom it may concern:

Be it known that I, HARRY PRICE, citizen of the United States, residing at Boston, in the county of Suffolk and State of Massachusetts, have invented new and useful Improvements in Oil Vaporizers and Burners, of which the following is a specification.

This invention relates to apparatus for vaporizing fuel oil and burning the vapor for heating purposes, the apparatus being adapted to be used particularly in a stove or furnace, and comprising an oil vaporizing chamber or retort having a vapor burner arranged to externally heat said retort, and thus vaporize the oil therein, and to supply heat for other purposes, means being provided for supplying heat to the retort.

The invention is embodied in the improved apparatus hereinafter described, having provisions for quickly vaporizing oil, and for burning the same, and also having provisions for preliminarily heating the chamber or retort, as in first starting the operation of the apparatus.

25 Of the accompanying drawings forming a part of this specification,—

Figure 1 is a top plan view of an oil vaporizer embodying the invention, adapted for use in a cooking stove.

30 Fig. 2 is a section on line 2—2 of Fig. 1.

Fig. 3 is a section on line 3—3 of Fig. 2.

Fig. 4 is a section on line 4—4 of Fig. 1.

Fig. 5 is an end elevation of the vaporizer shown by the preceding figure, and a section view showing portions of a cooking stove in which the vaporizer is installed.

35 Fig. 6 is a plan view, representing a form suitable for insertion in the fire-box of a furnace.

40 Fig. 7 is a fragmentary sectional view, illustrating a modification.

The same reference characters indicate the same or similar parts in all of the figures.

The embodiment of the invention shown 45 by Figs. 1 to 5, inclusive, comprises a vaporizing chamber or retort, including a vertically elongated hollow body 12, and a laterally extending hollow arm 13, communicating with the lower portion of the body 12.

50 In the embodiment of the invention here shown, there are two oppositely projecting

hollow arms 13, each being a duplicate of the other.

Oil is delivered to the body 12 from a suitable source of supply, such as an elevated 55 tank 14, through a pipe line 15, which may be provided with a needle valve 16, one end of said pipe line communicating with the body 12, and preferably with the lower end of a vertical oil conduit 17 (Fig. 4) forming 60 a part of said body, the upper end of said conduit communicating through an opening 18 with the upper portion of the body 12, so that oil supplied by the pipe line, rises in the body 12 to the upper portion 65 thereof, and then flows downwardly in said body to the arm 13.

19 represents a vapor burner communicating with the outer end of the arm 13, and arranged to direct its flame upwardly. 70

20 represents a flame deflector located above the burner 19, and arranged to direct a portion of the flame toward the adjacent surfaces of the body 12 and arm 13, and thus externally heat the vaporizing chamber and 75 vaporize the oil therein. Other portions of the flame are deflected in different directions by the deflector 20 to supply heat to a stove or furnace.

21 represents an elongated oil burner located under the body 12 and arm or arms 13, said burner being preferably formed as an open pan, in which oil may be burned to preliminarily heat the vaporizing chamber. The body 12 and the arm or arms 13 of said 85 chamber are preferably provided with substantially vertical flues 22, adapted to conduct heated products of combustion from the burner 21 through said body and arm or arms, and thus facilitate the vaporization of 90 the oil.

The deflector 20 is connected by a stem 23 with a horizontal intercepting plate 24, supported above the vaporizing chamber, and preferably composed of two substantially 95 circular end portions, and a neck connecting said portions, as shown by Fig. 1.

I prefer to adjustably support the deflectors 20 so that they may be adjusted toward and from the vapor burners 19. As 100 here shown, the plate 24 is provided with two slots 25 and 26. One edge of the slot 25

is beveled to form a tooth 27. The plate is provided at or near the other slot with a downwardly projecting dog 28. The body 12 is provided with two ratchet-toothed members 29 and 30, one projecting into the slot 25, and the other into the slot 26. The teeth of the member 29 are adapted to engage the slot edge 27, and the teeth of the member 30 are adapted to engage the dog 28. Provision is thus made for supporting the plate 24 and deflectors 20 at various heights above the vapor burners.

The vaporizing chamber and the oil burner 21 may be formed in a single casting, as indicated by Fig. 2, and the oil burner may rest upon the grate 32 of a cook stove, as shown by Fig. 5.

At the outset, a suitable quantity of oil is poured into the pan or oil burner 21, and ignited. When the products of combustion impinging on the exposed surface of the vaporizing chamber and on the walls of the flues 22 have sufficiently heated the chamber, oil is admitted through the pipe line 15, and is immediately vaporized, and is ignited at the vapor burner or burners 19. The flame from said burners, as already stated, externally heats the vaporizing chamber and thus continuously vaporizes the oil admitted thereto.

The body 12 is preferably externally corrugated, as shown by Fig. 3, the corrugations extending vertically and increasing the heat-absorbing surface area of the body.

The arm 13 is provided with a tapped socket 32 engaged with the screw-threaded tubular shank 33 of the burner 19, and surmounted by a cup 34 adapted to receive any oil which may flow unconsumed from the burner before the oil is vaporized, and provided with an outlet 35 permitting oil to flow into the pan or burner 21.

The intercepting plate 24 not only supports the deflectors 20 and spreads the flame from the burners, but also collects soot resulting from imperfect combustion, at the commencement of the operation, said plate being provided with a downwardly projecting marginal flange 24^a. The plate may be provided with a socket 24^b adapted to be engaged by a stove-cover lifter, so that it may be conveniently removed to dislodge soot, and manipulated to vary its height.

Fig. 6 represents a modification, in which the vaporizing chamber includes a body 12^a, arms 13^a connected with the body 12^a by hollow necks 13^b, vapor burners 19^a and deflectors 20^a located above said burners. A substantially triangular oil-burning pan 21^a is located under the vaporizing chamber.

Fig. 7 shows a body 12^b having an oil inlet 36 at its upper portion and a helical oil conduit 37, surrounding the body and communicating with the pipe line 15 and with the inlet 36. The conduit 37 forms, in

effect, a corrugated heat-absorbing surface exposed to heat from the vapor burner.

I claim:

1. An oil vaporizer comprising a vaporizing chamber, including a vertically elongated hollow body, and a laterally extending hollow arm communicating with the lower portion of said body and having a vapor burner, means for delivering oil to the upper portion of said body, the delivered oil flowing downwardly therein to said arm, a flame deflector located over the vapor burner, said burner and deflector being arranged to externally heat the said body portion and arm, and an oil burner located under said body and arm and arranged to preliminarily heat the same, said body and arm being provided with means for conducting therethrough heated products of combustion from the oil burner. 85

2. An oil vaporizer comprising a vaporizing chamber, including a vertically elongated hollow body, and a laterally extending hollow arm communicating with the lower portion of said body and having a vapor burner, means for delivering oil to the upper portion of said body, the delivered oil flowing downwardly therein to said arm, a flame deflector located over the vapor burner, said burner and deflector being arranged to externally heat the said body portion and arm, and a burner located under said body and arm and arranged to preliminarily heat the same, said body and arm being provided with substantially vertical flues arranged to conduct heated products of combustion therethrough. 95

3. An oil vaporizer comprising a vaporizing chamber, including a vertically elongated hollow body, and a laterally extending hollow arm communicating with the lower portion of said body and having a vapor burner, means for delivering oil to said body, a flame deflector located over the vapor burner, and an intercepting plate located above and holding said deflector, and means adjustably connecting said plate with the said body and permitting vertical adjustments of the plate and deflector relatively to the vapor burner. 110

4. An oil vaporizer comprising a vaporizing chamber, including a vertically elongated hollow body, and a laterally extending hollow arm communicating with the lower portion of said body and having a vapor burner, means for delivering oil to said body, a flame deflector located over the vapor burner, an intercepting plate connected with said deflector and provided with slots and with a dog adjacent to one of said slots, the said body being provided with toothed members, one adapted to engage an edge of one of said slots, and the other adapted to engage said dog. 120

5. An oil vaporizer comprising a vaporiz- 130

ing chamber, including a vertically elongated hollow body and a laterally extending hollow arm communicating with the lower portion of said body, and having a socket and an oil-receiving cup at its outer end provided with an oil outlet, a vapor burner engaged with said socket and surrounded by said cup, means for delivering oil to said body, and a pan-shaped burner located under said body and arm to supply heat thereto and arranged to receive oil escaping from said cup through the said oil outlet.

In testimony whereof I have affixed my signature.

HARRY PRICE.
